UNITED STATES PATENT OFFICE.

WILLIAM C. PRITCHARD, OF LANCASTER, PENNSYLVANIA.

REGISTER FOR PUMPS.

1,027,151.

Specification of Letters Patent.

Patented May 21, 1912.

Application filed February 13, 1911. Serial No. 608,267.

To all whom it may concern:

Be it known that I, WILLIAM C. PRITCHARD, a citizen of the United States, residing at Lancaster, in the county of Lancaster and State of Pennsylvania, have invented certain new and useful Improvements in Registers for Pumps, of which the following is a specification, reference being had therein to the accompanying drawing.

10 This invention relates to improvements in pumps, of that class which are self-measuring, and which are employed for dispensing liquids, such as oil or gasolene; and the invention relates more particularly to 15 the registering mechanism employed to record the quantity of liquid drawn during each sale.

The objects of the invention are to provide a registering mechanism that shall be 20 cheap, durable and efficient, and that shall not only register the quantity delivered by the pump upon each stroke, but automatically alarm or give warning to the operator when a prearranged quantity shall have 25 been recorded.

Another object is to provide a simple device whereby the registering mechanism may be reset to its normal position of zero from any position within its scope of registration.

30 Still another object of the invention is to provide a device of this class that will be capable of attachment to any style of pump having a movable piston and means for attaching the device thereto.

35 With these and other objects in view, my invention consists in certain construction and combination of parts as will hereinafter be fully described and claimed and illustrated in the accompanying drawings, which 40 form a part of this application, and in which like figures of reference refer to corresponding parts in all of the views; but it is fully understood that while I have here described my invention as shown, that I do

45 not confine myself to the exact design, as slight changes may be made in the construction and arrangement of the several parts without departing from the spirit of the invention.

In the drawings:—Figure 1, is a perspective view of a dispensing pump, embodying my invention. Fig. 2, is a detail rear view of the registering device in connection with the operating mechanism, attached to the pump piston. Fig. 3, is a vertical sectional view of the registering and alarming device, taken on the line X—X of Fig. 2.

Referring to the drawings, the pump which is mounted in the usual way upon a platform 1, or tank top, comprises the outlet pipe 2, to which is mounted the piston rod 3, and to the upper end of which is secured a rack-bar 4; while the lower end of the piston rod 3, is attached to and operates the usual suction cylinder in the tank (not illustrated). The piston rod 3, is reciprocated in a vertical manner by the hand-crank 5, which rotates a pinion (not shown) in mesh with said rack-bar 4. The outlet pipe 2, may be provided with a suitable valve or hose connection 6. Mounted in a suitable position, adjacent to the piston rod 3, is a computing or indicating chart 7, which may be divided and sub-divided in any suitable manner; while secured to said piston rod 3, or to said rack-bar 4, is an index finger or pointer 8, which extends across the face of the chart 7, and is adapted to travel up and down over the face of the chart 7, as actuated by the piston rod.

Attached to the pump frame 9, and adjacent to the top of the chart 7, is mounted my novel automatic register 10, which comprises a frame or casing 11, provided with an attaching base 12, and a central hub or boss 13, to one side of which is attached by the pivot screw 14, the removable cover plate 15; and to the other end of said hub 13, is secured by the screw 16, a gong or bell 17.

Mounted within the frame or casing 11, in a freely rotatable manner upon the pivot screw 14, is a ratchet wheel 18, which is provided with a hub 19, around which is wrapped a tension spring 20, having one of its ends secured to said ratchet wheel 18, and the other end to said frame or casing 11, in such a manner, that as said ratchet

wheel 18, is rotated within the casing 11, the spring tension will be increased until the further revolution of said ratchet wheel 18, is prevented by a suitable stop. To the 5 face of said ratchet wheel 18, is attached a dial 21, which is provided with a series of suitable numerals or characters indicating the quantity of liquid drawn by each stroke of the piston 3, from the tank; said numerals or characters being exposed to view 10 through an opening 22, in the removable cover plate 15.

In the construction herewith illustrated, the ratchet wheel 18, is provided with a series of teeth or notches 23, of even and regular length to correspond to every numeral on the dial 21, from and including I, to and including the numeral for indicating the largest quantity, and one short tooth 24, to correspond to the numeral indicating zero; said short tooth 24, being so placed with relation to the highest numeral on the dial, that when said numeral has been reached, said short tooth 24, will not extend sufficiently 15 to be engaged by the actuating pawl 25, which is mounted in an adjustable manner on the rack-bar 4; but said short tooth 24, is of sufficient length to be engaged by the locking pawl 26, as the ratchet wheel 18, is 20 being rotated by the downward stroke of the rack-bar 4, and piston rod 3.

The automatic alarm mechanism comprises the gong or bell 17, which is secured by the screw 16, to the hub 13, of the frame 35 11; a striking hammer 27, mounted on a resilient arm 28, secured by the clamp 29, to said frame 11. Said hammer 27, being provided with a slotted arm 30, engaged by a stud 31, on a pivoted arm 32, which arm 40 projects through a slot 33, formed in said frame 11; said pivoted arm 32, being operated against the tension of the hammer arm 28, by a lug 34, projecting from the side of the ratchet wheel, and so positioned as to 45 engage said arm 30, and draw back the hammer 27, just before, and release the same when the largest numeral is reached by the revolution of the ratchet wheel; the release of the arm 32, being accomplished by the lug 50 34, passing thereover, as the arm 32, travels in an arc of shorter radius than that of the lug 34; said lug 34, also after passing the arm 32, engages a stop on the frame 11, and prevents further movement of the 55 ratchet wheel 18, in that direction.

The registering or ratchet wheel 18, is operated only upon the downward stroke of the piston 3, and when the liquid has been discharged from the cylinder; and to rotate 60 said ratchet wheel 18, the pawl 25, is pivoted upon the upper end of the rack-bar 4, and provided with an adjustment screw 35,

and lock nut 36; said pawl 25, upon the downward stroke of the rack-bar 4, engaging a tooth of the ratchet wheel 18, through 65 an opening in the side of the case, and upon its upward stroke passing over said teeth. The outward swing or depth of engagement of said pawl 25, with the teeth of the ratchet wheel 18, is limited by a stop pin 40, 70 placed adjacent to its pivot point, and when said rack-bar 4, has reached the limit of its down stroke, the adjustment screw 35, will engage the top of the gear casing 11, thus swinging the pawl 25, from the path of the 75 ratchet wheel 18.

The locking or retaining pawl 26, is mounted upon the frame 11, in such a position that it engages the teeth of the ratchet wheel 18, and prevents backward movement 80 of said wheel until released by pressing downward on the finger lever 37, which is integral therewith, when the ratchet wheel 18, will return to zero as actuated by the tension spring 20.

Referring to Fig. 2, it will be seen that when the ratchet wheel 18, has been rotated by the action of the piston 3, and pawl 25, to register the highest number, the short tooth 24, will be in a position whereby it 90 cannot be engaged by the pawl 25, and thus the piston 3, can be operated independently of the registering mechanism until the ratchet wheel 18, is returned to zero, so that if the operator disregards the warning of 95 the gong, there will be no damage done by the operation of the pump.

As shown in Fig. 1, of the drawings, there is a computing scale or chart 7, of the usual form attached in connection with an indicating finger 8, secured to the rack-bar 4, 100 for indicating the price per gallon, etc.; said chart being divided as desired.

In operation, the register is always brought to zero, and upon each downward 105 stroke of the piston, the total number of the quantities of each stroke of the piston is registered. Thus it will be seen that the quantity of liquid drawn will be clearly shown and a correct register secured, there- 110 by avoiding errors of the salesman in charging for the product.

The device is especially useful in filling automobile tanks, which is readily accomplished by connecting a hose to the outlet 115 nozzle and running the same to the vehicle; and as before stated, the register will clearly show the quantity.

Having thus described my invention what I claim as new and desire to secure by Let- 120 ters Patent is:-

In a device of the character described, the combination with a pump piston rod, a register adjacent thereto, a supporting frame

therefor, a pawl pivoted upon said piston rod and adapted to operate said register at the finish of the discharging stroke of said piston rod, one end of said pivoted pawl adapted to contact with said frame upon the return stroke of said piston to release said means from said register.

In testimony whereof I affix my signature in presence of two witnesses.

WILLIAM C. PRITCHARD.
